CLAIM

The ornamental design for a notebook computer, as shown and described.

DESCRIPTION

FIG. 1 is a three-dimensional view of a notebook computer in an open configuration;

FIG. 2 is a top view of the notebook computer of FIG. 1 in a closed configuration;

FIG. 3 is a back view of the notebook computer of FIG. 1 in a closed configuration;

FIG. 4 is a front view of the notebook computer of FIG. 1 in a closed configuration;

FIG. 5 is a bottom view of the notebook computer of FIG. 1 in a closed configuration;

FIG. 6 is a right-side view of the notebook computer of FIG. 1 in a closed configuration; and,

FIG. 7 is a left-side view of the notebook computer of FIG. 1 in a closed configuration.

Broken lines shown in the drawings illustrate portions of the notebook computer, and form no part of the claimed design.
